Inventor
By Attorney *D. A. Dally.*

UNITED STATES PATENT OFFICE.

NORA SANDERS, OF READING, PENNSYLVANIA.

DESIGN FOR A SHOE-HEEL.

SPECIFICATION forming part of Design No. 28,087, dated December 28, 1897.

Application filed June 23, 1897. Serial No. 641,995. Term of patent 7 years.

To all whom it may concern:

Be it known that I, NORA SANDERS, a citizen of the United States, residing at Reading, in the county of Berks and State of Pennsylvania, have invented and produced a new and original Design for Shoe-Heels; and I do hereby declare the following to be a full, clear, and exact description of the same, reference being had to the accompanying drawing, forming a part thereof.

This invention relates to a new and original design for shoe-heels.

In the accompanying drawing the figure is a view in perspective illustrating my design for a shoe-heel.

In carrying out my design the forward corners *a* and *b* of a shoe-heel formed at the intersection of the vertical faces *c* and *d* are rounded, whereby the forward edge of the

bottom *e* is curved outwardly in the form of an arc of a circle, the rear edge of said bottom and the side or face *c* being curved, as shown. By rounding the corners *a* and *b* the lower edge of face *d* is also downwardly curved in the form of an arc of a circle. Where the curved edges of bottom *e* and face *d* intersect, the lines thereof are lost, thereby forming a "ball-surface" at the forward portion of the heel.

I claim as my invention—

The design for a shoe-heel, substantially as shown and described.

In testimony whereof I affix my signature in presence of two witnesses.

NORA SANDERS.
